UNITED STATES PATENT OFFICE.

CHARLES T. WESTLAKE AND CHARLES F. FREDE, OF ST. LOUIS, MISSOURI, ASSIGNEES TO
CLARENCE H. HOWARD, OF ST. LOUIS, MISSOURI.

DUMP-CAR-OPERATING MECHANISM.

No. 887,163.

Specification of Letters Patent.

Patented May 12, 1908.

Application filed January 16, 1908. Serial No. 411,122.

To all whom it may concern:

Be it known that we, CHARLES T. WESTLAKE and CHARLES F. FREDE, citizens of the United States, residing at St. Louis, in the 5 State of Missouri, have invented a new and useful Improvement in Dump-Car-Operating Mechanism, of which the following is a specification.

Our invention relates to mechanism for 10 operating the drop doors of a dumping-car, bin, storage elevator, or analogous receptacle, whether mounted on wheels or stationary, adapted to contain sand, earth, coal, ore, grain, or the like, and from which the 15 contents are discharged or dumped through an opening in the floor controlled by the said doors to either side of, and beneath the receptacle, and our invention applies particularly to such a receptacle having two 20 opposite side doors hinged to and dependent from the floor and adapted to form when closed, a V-shaped hopper beneath the said opening, combined with a pivoted balanced door adapted to lock the side doors in their 25 closed position, and to form a chute thereto in their open position, such as the arrangement described and shown in the Letters Patent granted to Herbert L. Aulls, April 16, 1907, number 850,719, for improvement in 30 convertible dumping-cars.

Our invention has for its object to enable the balanced door and one of the side doors to be opened simultaneously, and held in the open position for discharging the contents of 35 the car or receptacle to the corresponding side beneath the same, the other side door being at the same time held in its normal or closed position, and to enable either of the side doors to be closed initially in advance of 40 the balanced door.

The invention consists in features of novelty as hereinafter described and claimed, reference being had to the accompanying drawing forming part of this specification, 45 wherein,

Figure 1, is a top plan view of one end and adjacent part of a dump-car having our improved door operating mechanism applied thereto; Fig. 2, an end elevation of the car 50 partly broken away, and a side view of the operating mechanism; Fig. 3, a vertical transverse section through the car and doors on line 3, 3, in Fig. 1, and Figs. 4, and 5, side views of the operating mechanism corre-

sponding to Fig. 2, in the opened and closing 55 positions respectively, of the doors.

Like letters and numerals of reference denote like parts in all the figures.

a represents a dump-car having preferably, at each side through the floor 1, a series of 60 longitudinally successive rectangular-shaped openings 2 for the discharge therethrough of the contents of the car *a*, the floor 1 at and between the two opposite series of openings 2 being triangular-shaped in cross section 65 having its apex or ridge at a suitable height from the openings 2 or floor base, and coincident with the longitudinal center of the car *a*, for insuring the dump or discharge of the contents of the latter by gravity through the 70 openings 2 without shoveling or plowing, substantially as shown and described in the said patent.

Extending longitudinally through the car *a* at the sides respectively of each opening 2, 75 and rotatable in bearings 3 formed in or fixed to the floor 1 thereat, is a shaft 4 to which is fixed a door *b* dependent from the floor 1, and having its upper longitudinal edge or member corresponding to, and in juxtaposition to the side of the opening 2, the two opposite doors *b* of each opening 2, on partly rotating the shafts 4, being adapted to close together along their lower or free longitudinal edges or members so as to form a V-shaped 85 hopper *c* beneath the opening 2. Immediately beneath the hopper *c* thus formed and extending longitudinally through the car *a* midway between the shafts 4, is a shaft 5 rotatable in bearings 6 fixed to the car *a*, 90 and on the shaft 5 is fixed a balanced door or locking-plate *d* of suitable width and preferably corresponding in length to the doors *b* and openings 2, the balanced door *d* when horizontal being adapted to bear longitudinally at its middle portion against the lower free edges or members of the doors *b* and thereby hold or lock the latter in their closed position, as shown particularly in Fig. 2, and to be moved transversely thereat about the 100 said edges radially to the axial bearings 6 of the shaft 5, for releasing and allowing either of the doors *b* to be opened and the other door *b* held closed, as hereinafter more particularly referred to.

On each shaft 4, preferably on the outside of the end wall 7 of the car *a*, is fixed at right angles to the inner face of the corresponding 105

side door *b*, an arm 8, and on the shaft 5 in the plane of and inclined toward each arm 8, is fixed a similar arm 8', the arm 8 of one of the side doors *b* (the outside door *b* in the present case) and the corresponding arm 8' on the shaft 5 being coupled together preferably at their free ends respectively, by two connected links or toggle-bars 9, 9'. To the link 9, preferably midway between its connection 10 to the arm 8 and link 9', is coupled the lower end of a rod or pitman 10 having its upper end coupled to the free end of the outer arm 11 of a lever *e* preferably of the first order, which is fulcrumed to a bracket 12 fixed to 15 the car *a*, the inner arm 11' of the lever *e* being coupled at its free end to the piston-rod 13 of a piston (not shown) contained within an upright cylinder 14 fixed to the car *a*, and adapted to be raised and lowered therein by 20 steam, compressed air, or other suitable motive fluid supplied to the cylinder 14 through pipes 15 from any available source. Or the piston with its rod 13 may be raised and lowered by hand in lieu of steam as hereinafter 25 described.

The piston rod 13, when operated by the piston within the cylinder 14, is slidable at its outer free end portion above the point of its connection to the lever *e*, through a block 30 16, held stationary in this case, but otherwise movable vertically in guides 17, by an upright circular rod 18 which is screw-threaded through, and for a suitable distance above the block 16, and adapted to rotate 35 between collars 19 in a bearing 20 fixed to the car, by a handwheel 21 fixed on the upper end of the rod 18, so that, in case it is desired to operate the lever *e* by hand in lieu of by fluid pressure on the piston, the piston- 40 rod 13 is fixed to the block 16 by a pin 22, when by turning the rod 18 by its hand-wheel 21 the block 16 is raised or lowered in its guides 17 by the screw-threaded portion of the rod 18, and with it the piston-rod 13 and 45 lever *e*.

In operation, assuming the side doors *b* to be closed and locked by the balanced door *d* in its horizontal position, as seen in Fig. 2, and it being desired to open the outside door 50 *b* for discharging the contents of the car *a* through the opening 2 to the corresponding side thereof beneath the car *a*, the piston-rod 13 with the inner arm 11' of the lever *e* is raised and the outer arm 11 of the latter with 55 the pitman 10 thereby lowered, which causes the outside door *b* and balanced door *d* to be released and simultaneously swung downward and apart from each other radially to the bearings of their respective shafts 4 and 60 5, until they reach the limit of their stroke, or are fully opened as seen in Fig. 4, the balanced door *d* at the same time holding the inside door *b* closed, and forming therewith a chute for directing the contents of the car *a* 65 discharged through the opening 2, to the side

of the car *a*. For closing the outside door *b* and balanced door *d*, the piston-rod 13 is lowered and raises the outer arm 11 of the lever *e*, which causes the pitman 10, owing to the leverage at its connection with the link 9 70 from the shaft 4 being greater than its leverage from the shaft 5, to raise the arm 8 and outside door *b* in advance of the arm 8' and balanced door *d*, until the outside door *b* approximates its closed position as seen in Fig. 75 5, when the doors *b* and *d* will be further raised together and closed simultaneously, or thereabout, into the position seen in Fig. 2. Conversely, if desired to open the other or inside door *b* and hold the outside door *b* 80 closed, for directing the contents of the car *a* inward beneath the same, the links or toggle-bars 9, 9', are disconnected from the arms 8 and 8' of the outside door *b* and connected in like manner to the corresponding arms 8 85 and 8' of the inside door *b* as indicated by dotted lines to the right in Fig. 2, and the operation repeated, the jaw at the connection of the pitman 10 with the link 9 being sufficiently long in this case for allowing the 90 link 9 to be thrown over or reversed about its joint with the pitman 10 for connecting with the arm 8 of the inside door *b*.

What we claim as our invention and desire to secure by Letters Patent is:—

1. In a dump-car or analogous receptacle having a discharge opening, the combination of two opposite rotatable shafts extending along, and at or adjacent to two opposite sides of the said opening, two opposite side 95 doors fixed to and dependent from the said shafts and adapted to meet at the bottom in their closed position so as to form a V-shaped hopper beneath the said opening, a lower rotatable shaft extending along beneath the 100 said opening between its said sides, bearings for the shafts fixed to the car, a balanced door fixed to the said lower shaft and adapted to bear against the bottom of the side doors in their closed position, an arm on one of the 105 first named shafts and a corresponding arm on the lower shaft, two toggle-bars connecting the said arms together, a pitman connected to one of the said bars, and means for raising and lowering the said pitman, substantially as described and for the purpose set forth.

2. In a dump-car or analogous receptacle having a discharge opening, the combination of two opposite rotatable shafts extending along, and at or adjacent to two opposite sides of the said opening, two opposite side 110 doors fixed to and dependent from the said shafts and adapted to meet at the bottom in their closed position so as to form a V-shaped hopper beneath the said opening, a lower rotatable shaft extending along beneath the 115 said opening between its said sides, bearings for the shafts fixed to the car, a balanced door fixed to the lower shaft and adapted to bear 120

against the bottom of the side doors in their closed position, an arm on one of first named shafts and a corresponding arm on the lower shaft, two toggle-bars connecting the said arms together, a pitman connecting one of the said bars to a lever fulcrumed to the car, and means for raising and lowering the said lever about its fulcrum, substantially as described and for the purpose set forth.

10 3. In a dump-car or analogous receptacle having a discharge opening, the combination of two opposite rotatable shafts extending along, and at or adjacent to two opposite sides of the said opening, two opposite side doors fixed to and dependent from the said shafts and adapted to meet at the bottom in their closed position so as to form a V-shaped hopper beneath the said opening, a lower rotatable shaft extending along beneath the 15 said opening between its said sides, bearings for the shafts fixed to the car, a balanced door fixed to the said lower shaft and adapted to bear against the bottom of the side doors in their closed position, means for opening one of the side doors and the balanced 20 door simultaneously and holding them in the open position, means for closing the last named side door initially in advance of the balanced door, and for holding the other side door closed during the said movements of the balanced door, substantially as described.

4. In a dump-car or analogous receptacle having a discharge opening and doors therefor, the combination of a lever fulcrumed to the car, a rod coupled to the lever and movable longitudinally, a block fixed to the rod, a rotatable rod screw-threaded through the block in alinement with or parallel to the first named rod, and held from longitudinal 35 movement, suitable bearings for the said rods and block respectively, fixed to the car, means for connecting the lever to the said doors, and for rotating the screw-threaded rod by hand, substantially as described.

45 5. In a dump-car or analogous receptacle having a discharge opening, the combination of two opposite rotatable shafts extending along, and at or adjacent to two opposite sides of the said opening, two opposite side doors fixed to and dependent from the said shafts and adapted to meet at the bottom in their closed position so as to form a V-shaped hopper beneath the said opening, a lower rotatable shaft extending along beneath the 50 said opening between its said sides, bearings for the shafts fixed to the car, a balanced door fixed to the lower shaft and adapted to bear

against the bottom of the side doors in their closed position, an arm on one of the first named shafts and a corresponding arm on the lower shaft, two toggle-bars connecting the said arms together, a pitman connecting one of the said bars to a lever fulcrumed to the car, a cylinder fixed to the car and closed at each end, a piston within the cylinder, a rod projecting from the piston through one end of the cylinder and coupled to the said lever, and means for raising and lowering the piston within the cylinder, substantially as described and for the purpose set forth. 65

6. In a dump-car or analogous receptacle having a discharge opening, the combination of two opposite rotatable shafts extending along, and at or adjacent to two opposite sides of the said opening, two opposite side doors fixed to and dependent from the said shafts and adapted to meet at the bottom in their closed position so as to form a V-shaped hopper beneath the said opening, a lower rotatable shaft extending along beneath the 70 said opening between its said sides, bearings for the shafts fixed to the car, a balanced door fixed to the lower shaft and adapted to bear against the bottom of the side doors in their closed position, an arm on one of the first named shafts and a corresponding arm on the lower shaft, two toggle-bars connecting the said arms together, a pitman connecting one of the said bars to a lever fulcrumed to the car, a rod coupled to the lever and movable longitudinally, a block fixed to the rod, a rotatable rod screw-threaded through the block in alinement with or parallel to the first named rod and held from longitudinal movement, suitable bearings for 75 the said rods and block respectively, fixed to the car, and means for rotating the screw-threaded rod by hand, substantially as described and for the purpose set forth. 80

7. In a dump-car or analogous receptacle having a discharge opening, and two pivoted doors therefor, means for opening the said doors simultaneously and holding them in the open position, and means for closing one of the said doors initially in advance of the other door, substantially as described. 100

In testimony whereof we have signed our names to this specification in the presence of two subscribing witnesses.

CHARLES T. WESTLAKE.
CHARLES F. FREDE.
